UNITED STATES PATENT OFFICE.

CHESTER R. WILLIAMS, OF BEDFORD, OHIO.

TRACTION-LENDING CONTRIVANCE.

1,159,560.

Specification of Letters Patent.

Patented Nov. 9, 1915.

Application filed September 10, 1914. Serial No. 861,147.

To all whom it may concern:

Be it known that I, CHESTER R. WILLIAMS, a citizen of the United States, residing at Bedford, in the county of Cuyahoga and 5 State of Ohio, have invented a new and useful Improvement in Traction-Lending Contrivances, of which the following is a specification, the principle of the invention being herein explained and the best mode in which 10 I have contemplated applying that principle, so as to distinguish it from other inventions.

My invention relates broadly to a contrivance capable of establishing traction for 15 a vehicle.

More particularly its purpose is to furnish a traction effect in aid of automobiles whose tires are not otherwise enabled to have a sustained bite upon a given road surface.

I have had as an incidental object the provision of a contrivance which embraces the following features: 1. Efficiency in operation. 2. Standardized component parts. 3. 25 Simplicity, durability and economy of construction. 4. Extreme compactness when disassembled. 5. Facility of assemblage. 6. Reversibility in function to suit conditions. 7. Adaptability of one of its parts 30 to a distinct use in conjunction with a tool found in all motor vehicle equipments.

The inventive conception is associated with means which are hereinafter explained and variously combined in the claims.

While the annexed drawing and particular description thereof, set forth the preferred and modified form embodying my invention, it should be understood that the means only exemplify some of many diversified mechanical forms with which the principle of my invention may be properly applied.

Figure I is a plan of the preferred form of one part of my invention. Fig. II is a section on line II-II of Fig. I. Fig. III is a plan of a complete embodiment assembled for use. Fig. IV is a section on line IV-IV of Fig. III. Fig. V is a plan of a modified assemblage of the several elements featuring my idea. Fig. VI is a section on line VI-VI of Fig. V. Fig. VII is a plan of a graded roadway showing the application of my invention to a specific hindering condition. Fig. VIII is a vertical section on line VIII-VIII of Fig. VII, viewed in the direction indicated. Fig. IX

is a similar view illustrating the adaptability of my invention to a traction difficulty of a different character. Fig. X is a vertical section on line X-X of Fig. IX 60 looking in the direction of the arrows.

The principal part of my invention consists in a metal plate 1 of standard corrugated design wherein the spacing of the rows of corrugations is a few inches in extent. I prefer to employ plates of rectangular shape having one pair of oppositely disposed side edges 2 somewhat longer than the others 3.

I have designated the depressions on any 70 particular face of the plate as 4 and the ridges as 5. In corrugated sheets of standard manufacture those edges which are parallel with the direction of extent of the corrugations are always arranged to be in substantially the same plane and for my purpose such edges will be considered as disposed below, as suggested in Figs. I and II. Each of the four corners of the plate 1, is 75 provided with an opening 6.

In practice I contemplate the use of a plurality of plates of similar form so that when 80 separate they may be superimposed and transported together as a small package. The plates are to be secured together end to end in any suitable manner though preferably so as to constitute together a flexible composite whole. Such an attachment may be accomplished by interlacing a wire rope 7 through a series of openings 6 alined so 85 that different pairs register. The ends of the rope 7 may, if found necessary, be secured to the ground by means of long spikes 8. It will be seen that Figs. III and IV show a series of plates 1 assembled so that 90 the corrugations run lengthwise whereas Figs. V and VI show the corrugations extending crosswise with reference to the combined extent.

For the exemplifying purpose required 100 here, I have illustrated two distinct kinds of traction difficulties which my invention effectually overcomes.

Directing attention then next to Figs. VII and VIII which illustrate the mode of utilizing the assembled formation of Figs. III and IV, it will be assumed that a graded roadway 9 having gutters 10 has afforded such poor traction as to cause the rear end 105 of an automobile chassis 11 to skid and swing down toward one of the gutters 10. The front wheels 12 are readily maintained

upon the upper portion of the roadway, but the hind wheels 13 will have been carried down by the momentum of the vehicle into the position shown. Under such circumstances my contrivance may be speedily assembled according to Fig. III and lain under the lowest hind wheel so as to extend diagonally upward toward the center of the road. The wheel is thereby furnished traction and precluded of lateral skidding while ascending because of its engagement with the pair of continuous ridges between which it tends to wedge itself. The forward end of my contrivance employed in this wise is seen to be secured to the ground through the agency of the free ends of the rope 7 and spikes 8. The plates themselves of course grip the soil and the rear edges 3 tend to retard lengthwise movement. Preparatory to placing the rear end of my inventive construction under a wheel, one of the plates well serves as a base for a lifting jack.

The views depicted by Figs. IX and X disclose the manner of employing my invention on another road 14 in case one or more wheels have settled in a rut 15 which offers no traction. Recourse is then had to the other mode of connecting after the manner of Fig. V. The flexibility of the whole permits it readily to conform to the forward slope of the rut and thereafter the wheel to climb from one corrugation to another.

I claim:

1. A traction-lending contrivance comprising a plurality of plates having both sides corrugated, each of said plates being provided with a number of openings, and means for connecting different combinations of said openings for the purpose specified.
2. A traction-lending contrivance comprising a plurality of corrugated plates, means including a rope for loosely connecting an end of each plate to another, the arrangement being such that the corrugations of all the plates extend in the same direction.
3. A traction-lending contrivance comprising a plurality of plates of zig-zag cross section, means for connecting an end of each plate to another in overlapped position, the corrugations of all of said plates extending in the direction of alinement of said plates, whereby relatively transverse ridges are provided.
4. A traction-lending contrivance comprising a plurality of corrugated plates having end portions, each provided with an opening, each of said plates being lapped with respect to another whereby such openings register, a rope interlaced through said openings, and means for securing the ends of said rope to the ground.
5. A traction-lending contrivance comprising a member having its under surface fashioned with projections and depressions, and means for securing the same to the

ground a given distance beyond opposite ends thereof.

6. A traction-lending contrivance comprising a plurality of tie portions arranged in a row, and a pair of flexible binder portions connecting the ends of said tie portions respectively, and means for securing one end of the whole to the ground. 70

7. A traction-lending contrivance comprising a plurality of tie portions arranged in a row, and distinct means flexibly connecting the corresponding ends of said tie portions, the whole presenting a roughened surface in a direction transverse to the plane of such row. 75

8. A traction-lending contrivance comprising a pair of plates having perforate end portions, one of said plates being lapped with respect to the other, and a rope interlaced through said openings, the upper surfaces of said plates being fashioned with projections and depressions for the purpose specified. 80

9. A traction-lending contrivance comprising a pair of rope lengths, and a plurality of interconnecting metal plates, the arrangement being such that the whole is flexible and detachable into its several elements. 85

10. A traction-lending contrivance comprising a pair of metal plates having ridges above, and means loosely connecting any given pair of edges of said plates together whereby to alter the relation of the ridges of different plates for the purpose specified. 90

11. A traction-lending contrivance comprising a pair of corrugated metal plates, a device connecting any given pair of edges of said plates together whereby to alter the relation of the corrugations of different plates, and means associated with said device for securing one end of the assembled plates to the ground. 95

12. A traction-lending contrivance comprising a pair of similarly corrugated metal plates whereby to have corresponding surfaces conform to each other, and means for attaching said plates to each other in either of two positions. 100

13. A traction lending contrivance comprising a plurality of plates for zig-zag cross section adapted for arrangement in a row upon an inclined portion of roadway, and means loosely connecting proximate edges of said plates whereby the contrivance may conform to the supporting portion of such roadway. 115

14. A traction lending contrivance comprising a plurality of corrugated plates adapted for arrangement in a row diagonally up an inclined roadway, the corrugations of adjacent plates forming continuations of each other, and means loosely connecting proximate edges of said plates whereby opposite longitudinal edges of the 120

130

contrivance in its entirety may conform to the supporting portion of such roadway.

15. A traction-lending contrivance comprising an elongated structure provided with longitudinally extending and parallel grooves and protuberances adapted to be applied diagonally upon an inclined roadway.

16. A traction-lending contrivance comprising an elongated structure provided above with longitudinally extending and parallel grooves and protuberances adapted to be applied diagonally upon an inclined roadway, the under surface of said structure being fashioned with projecting ridges adapted to enter the soil.

17. A traction-lending contrivance comprising a plurality of corrugated plates, means loosely connecting said plates, the arrangement being such that the corrugations of the several plates form together a corresponding number of continuous grooves and

protuberances, the latter adapted to be applied diagonally up an inclined roadway.

18. A traction-lending contrivance comprising a pair of corrugated plates, one plate being partly lapped relative to the other plate to form a ridge, and a device flexibly connecting said plates whereby the contrivance as a whole may conform to the supporting portion of the roadway.

19. A traction-lending contrivance comprising a plurality of plates, the latter being of zig-zag cross section and adapted to be superposed compactly together, and detachable means for flexibly connecting said plates in a row, adjacent plates being overlapped.

Signed by me, this fifth day of September, 1914.

CHESTER R. WILLIAMS.
